(57) **CLAIM**

We claim the ornamental design for a handrail, as shown and described.

DESCRIPTION

FIG. 1 is a front perspective of a handrail in accordance with the present design;

FIG. 2 is a front view thereof;

FIG. 3 is a back view thereof;

FIG. 4 is a right side view thereof;

FIG. 5 is an end view taken from along lines 5-5 of FIG. 2;

FIG. 6 is a top view of the handrail; and,

FIG. 7 is a bottom view of the handrail.

Broken lines and unshaded portions entirely contained within broken lines are not claimed. The dot-dash lines in the drawings form a boundary of the claimed design.
